Specification for Design.

Patented Oct. 25, 1910.

Application filed July 25, 1910. Serial No. 573,818. Term of patent 7 years.

To all whom it may concern:

Be it known that I, FREDERICK S. STAFFORD, a citizen of the United States, and resident of Dallas, in the county of Dallas and State of Texas, have invented an ornamental Design for Automobile-Lamps, of which the following is a specification, reference being had to the accompanying drawing, forming a part thereof.

In these drawings, Figure 1 is a top view

of the lamp, Fig. 2 is a front view thereof, and Fig. 3 is an end view,

I claim—

The ornamental design for an automobile lamp as shown.

FREDERICK S. STAFFORD.
